WELL BIT

Application filed August 30, 1929. Serial No. 389,429.

This invention has to do with a bit and relates more particularly to a bit suitable for drilling wells. It is a general object of the present invention to provide a simple, practical, inexpensive bit construction employing a shank and a detachable drilling head.

A general object of the present invention is to provide a bit embodying a shank for attachment to a drill stem, a head embodying a cutting member or teeth, and a simple, effective and practical means for detachably connecting the head and shank.

It is an object of the invention to provide a bit of the character mentioned in which the shank and head are connected so that driving strains are effectively transmitted from the shank to the head.

It is another object of the present invention to provide a bit of the character mentioned in which the head is attached to the shank so that it is effectively and dependably held on the shank, eliminating danger of loss of the head in the well.

Another object of the invention is to provide a simple, practical and improved locking means for securing a drilling head on a shank. The invention provides a construction that is simple of manufacture, easily handled, and dependable in operation.

It is a further object of the invention to provide a bit head in which the cutting parts are formed and related so that they are particularly effective and efficient in drilling.

The various objects and features of my invention will be best and more fully understood from the following detailed description of a typical form and application of the invention, throughout which description reference is had to the accompanying drawing, in which:

Fig. 1 is a view of the bit provided by this invention showing the shank and head separated and in position ready to be arranged together. Fig. 2 is a view showing the shank and head in the process of being arranged together. Fig. 3 is a view showing the shank and head of the bit arranged together in operating position with the head locked on the shank. Fig. 4 is a bottom view of the head

showing the arrangement of teeth on the head. Fig. 5 is a transverse sectional view taken substantially as indicated by line 5-5 on Fig. 2. Fig. 6 is a transverse sectional view taken as indicated by line 6-6 on Fig. 5. Fig. 7 is a transverse sectional view taken as indicated by line 7-7 on Fig. 3, and Fig. 8 is a vertical sectional view through the lower portion of the head showing the manner in which the head fits the shank and the shape of certain of the teeth provided on the head. 55 60 65

The bit provided by the present invention includes, generally, a shank A, a head B, and means C for securing or locking the head 65 on the shank.

The shank A is in the nature of a mounting or carrier for the head B and includes, generally, a lower portion 10 to receive and carry the head B and an upper portion 11 adapted to be connected with a drilling string, for instance, to the lower end of a drill collar, or the like. The lower end portion 10 of the shank A is round in cross section and has a flat lower end 12. The upper end portion 11 of the shank is provided with means for making connection with a drilling string, for instance, in the case illustrated, it is provided with a tapered screw-threaded pin projection 13 to connect with a part such as a drill collar, or the like. The upper end portion 11 of the shank is enlarged at its lower end forming an enlargement 11^a overhanging the lower end portion 10 of the shank to present a downwardly facing shoulder 14. 70 75 80 85

The head B provided for application to the shank A includes a sleeve portion 15 adapted to surround the lower portion 10 of the shank A, a lower portion or extension 16 of the sleeve projecting below the shank A, and a plurality of teeth or cutting parts. The sleeve 15 has a central opening 17 round in cross section and proportioned to accurately receive the lower portion 10 of the shank A. The upper end 18 of the sleeve 15 is flat and adapted to fit the shoulder 14 of the shank. In the preferred construction the outside diameter of the sleeve corresponds to that of the enlargement 11^a of the shank A. 90 95 100

shank so that when the sleeve is in operating position on the shank the enlargement and sleeve present a continuous structure as shown in Fig. 3.

5 The lower end portion or continuation 16 of the sleeve 15 projects or continues downwardly beyond the lower end of the shank portion 10 and preferably projects inwardly from the sleeve 15 to present a shoulder 19 to fit the lower end 12 of the shank portion 10. In practice the part may be finished so that the upward thrust of the head B is taken by the end 18 of the sleeve engaging the shoulder 14, or by the shoulder 19 engaging 15 the end 12 of the shank, or both.

In accordance with the broader principles of the invention, various types and forms of teeth or cutting parts may be applied to the head. In the case illustrated there are two 20 pairs of outer cutting teeth 20 projecting downwardly from the lower end of the sleeve extension 16 and two inner teeth 21 located between the pairs of outer teeth and projecting downwardly from the sleeve extension 16.

25 The teeth 20 are preferably formed integral with the sleeve extension 16 and extend inwardly and rearwardly with reference to the periphery of the bit and direction of rotation of the bit as indicated by the arrow in Fig. 4. The two teeth 20 of each pair are located more or less closely one behind the other, and two pairs of teeth are located diametrically opposite each other. The outer teeth 20 project a suitable distance outwardly beyond the exterior of the sleeve 15 and sleeve extension 16 and extend inwardly as far as the inside of the sleeve extension 16. The inner teeth 21 are preferably pitched or located so that they are substantially 30 radial with reference to the central axis of the bit. The outer ends or outermost parts of the teeth 21 are substantially in line with the exterior of the sleeve 15 and sleeve extension 16, as shown in Fig. 4 of the drawing.

35 40 The teeth 21 extend inwardly across the bottom of the bit to a point somewhat inward of the inside of the sleeve extension 16 and then have parts 21^a extending upwardly and inwardly to points within the sleeve extension 16. The teeth 21, like the teeth 20, project a suitable distance downwardly below the sleeve extension 16. The upwardly and inwardly extending portions 21^a of the inner teeth are designed to remove the core or center left standing by the outer teeth 20 and the principal parts 21 of the inner teeth.

In accordance with the present invention a central circulation opening 25 extends 45 downwardly through the shank A and discharges into the sleeve extension 16 above the teeth, as will be apparent from inspection of the drawing. Circulation fluid being discharged within the sleeve extension circulates 55 outwardly between the teeth, and thus op-

erates to keep the space between the teeth washed clean.

The means provided by the present invention for securing or locking the head B on the shank A includes, generally, one or more lugs 30 on the shank A cooperating with bayonet type openings in the head and keys 31 for closing the openings to hold the lugs 30 therein. In the form of the invention illustrated I have provided two lugs 30 and 70 cooperating bayonet slots located diametrically opposite each other. I will proceed with a detailed description of but one lug and slot.

The lug 30 projects from the side wall of the lower portion 10 of the shank A and is preferably located a short distance from the lower end 12 of the portion 10. The opening in the head to receive the lug includes a vertical passage 32 for admitting the lug, and a lateral socket 33 at the lower end of the passage to receive and hold the lug. The passage 32 extends downwardly in the sleeve 15 from its upper end and is sufficiently large to freely pass the lug 30. The socket 33 projects laterally and in a forward direction (with reference to the direction of rotation of the tool) from the lower end of the passage. The socket 33 is shaped and proportioned to accurately receive the lug, 90 it being preferred to shape the forward side 30^a of the lug 30 and the corresponding wall 33^a so that they are radial with reference to the central axis of the bit. The rear side 30^b of the lug 30 is preferably shaped to be in line with and form a continuation of a side of the passage 32 when the lug is in operating position in the socket. The key 31 is adapted to be arranged in the passage 32 to project downwardly back of the lug 30 to hold the lug in operating position in the socket 33. The key 31 is adapted to be lowered into the passage 32 and preferably extends back of the lug and completely fills the passage when in operating position as shown throughout the drawing. The walls of the passage 32 and the rear side 30^b of the lug, which forms a continuation of one of the walls of the passage, are preferably made parallel, as shown in the drawing, so that the key 31 can be substantially rectangular in cross section and thus simple of manufacture.

The enlarged part 11^a of the shank A is provided with a groove or channel 40 which is in line with the passage 32 when the parts are in operating position as shown in Fig. 3. The channel 40 is provided to accommodate the key 31 to allow it to be arranged in and removed from the passage.

Suitable means is provided for securing the key 31 in operating position, for instance, in the case illustrated a stop screw 45 provided with a lock washer 46 is screwed into the shank A at the lower end of the channel 40 so that it is immediately above the

upper end of the key 31 to prevent the key from moving upwardly in the passage. The key may be held from lateral displacement in the passage by enlarging the sleeve 15 at the passage so that it has a wall 50 covering or extending over the sleeve in the manner clearly illustrated throughout the drawing.

In using the bit provided by this invention the head is applied to the shank A and locked thereon by means of the keys 31. When the keys are in place and the stop screws 45 applied, as shown in the drawing, the head is securely and dependably fixed on the shank. When the tool has been run and it is desired to remove the head from the shank for purpose of repair or replacement, it is a simple matter to remove the stop screws 45 and the keys 31, allowing the head to be removed from the shank. The lugs 30 are preferably integral with the shank so that the driving strains are communicated directly from the shank to the head, thus minimizing the danger of failure. It will be obvious that heads of various sizes and of various types may be applied to a shank, and it will also be apparent that the heads may be of simple, inexpensive construction, making the bit economical and of marked commercial value.

Having described only a typical preferred form and application of my invention, I do not wish to limit myself to the specific details set forth, but wish to reserve to myself any changes or variations that may appear to those skilled in the art or fall within the scope of the following claims.

Having described my invention, I claim:

1. In a well tool, two parts adapted to be subjected to torsion tending to cause relative rotation between them, one part having an opening adapted to receive a portion of the other part and having an external projection by means of which the torsional strain is put upon it, an enlargement on said section immediately forward of the projection relative to the direction of said strain, there being a passage in the wall of the opening radially inward of the enlargement and a lateral socket located inward and forward of the said external projection and communicating with the passage, and a lug on said portion of the other part adapted to be passed through said passage into the socket to transmit the torsional strain from one part to the other.

2. In a well tool, two parts adapted to be subjected to torsion tending to cause relative rotation between them, one part having an opening adapted to receive a portion of the other part and having an external projection by means of which the torsional strain is put upon it, there being a passage in the wall of said opening and a lateral socket located inward and forward of said projection relative to the direction of said strain, a lug on said portion of the other part adapted to be passed

through said passage and into the socket to fit the same, and removable means holding the lug in the socket whereby the lug transmits the torsional strain between the parts.

3. In a well tool, two parts adapted to be subjected to torsion tending to cause relative rotation between them, one part having an opening adapted to receive a portion of the other part and having an external projection by means of which the torsional strain is put upon it, there being a passage in the wall of said opening and a lateral socket located inward and forward of said projection relative to the direction of said strain, a lug on said portion of the other part adapted to be passed through said passage and into the socket to fit the same, and a key filling the passage to hold the lug in the socket.

4. In a well tool, two parts adapted to be subjected to torsion tending to cause relative rotation between them, one part having an opening adapted to receive a portion of the other part and having an external projection by means of which the torsional strain is put upon it, there being a passage in the wall of said opening and a lateral socket located inward and forward of said projection relative to the direction of said strain, a lug on said portion of the other part adapted to be passed through said passage and into the socket to fit the same, and a key filling the passage to hold the lug in the socket, the forward side of the lug fitting against a wall of the socket and extending radially of the central axes of the parts.

5. In a well tool, two parts adapted to be subjected to torsion tending to cause relative rotation between them, one part having an opening adapted to receive a portion of the other part and having an external projection by means of which the torsional strain is put upon it, an enlargement on said section immediately forward of the projection relative to the direction of said strain, there being a passage in the wall of the opening radially inward of the enlargement and a lateral socket located inward and forward of the said external projection and communicating with the passage, a key filling the passage to hold the lug in the socket, and a part on the said enlargement covering the passage.

6. In a well tool, two parts adapted to be subjected to torsion tending to cause relative rotation between them, one part having an opening adapted to receive a portion of the other part and having an external projection by means of which the torsional strain is put upon it, there being a passage in the wall of said opening and a lateral socket located inward and forward of said projection relative to the direction of said strain, a lug on said portion of the other part adapted to be passed through said passage and into the socket to fit the same, a removable key in the passage holding the lug in the socket, and a detach-

able means positively preventing displacement of the key from the passage.

7. In a well tool, two parts adapted to be subjected to torsion tending to cause relative rotation between them, one part having an opening adapted to receive a portion of the other part and having an external projection by means of which the torsional strain is put upon it, there being a passage in the wall of said opening and a lateral socket located inward and forward of said projection relative to the direction of said strain, a lug on said portion of the other part adapted to be passed through said passage and into the socket to fit the same, the said other part having a shouldered enlargement for engaging an end of the first mentioned part, and a key in the passage holding the lug in the socket, there being a channel in the said shouldered enlargement to admit the key into the passage.

In witness that I claim the foregoing I have hereunto subscribed my name this 21st day of August, 1929.

JESSE C. WRIGHT.
